[57] CLAIM

The ornamental design for a seating system, as shown and described.

DESCRIPTION

FIG. 1 is a perspective view of a seating system incorporating my new design, wherein the seat and back rest members are broken away to indicate indeterminate lengths;

FIG. 2 is a front elevation view thereof;

FIG. 3 is a rear elevation view thereof;

FIG. 4 is a side elevation view thereof, the opposite side being a mirror image;

FIG. 5 is a top plan view thereof; and,

FIG. 6 is a bottom plan view thereof.

The inner portions of the arm rest members which are not seen are mirror images of the outer portions.
